PENDANT FOR AN EARRING OR THE LIKE

Ross E. Elliott, Jr., Terre Haute, Ind.

Application February 16, 1955, Serial No. 34,530

Term of patent 14 years

(Cl. D45—9)

FIG 2

Fig. 1 is a plan view of a pendant for an earring or the like showing my new design; and

Fig. 2 is a vertical section view thereof taken on lines 2—2 of Fig. 1 in the direction of the arrows.

I claim:

The ornamental design for a pendant for an earring or the like, as shown.
